UNITED STATES PATENT OFFICE.

ASHLEY C. BENNETT, OF MINNEAPOLIS, MINNESOTA.

INTAKE-MANIFOLD.

1,103,931.

Specification of Letters Patent. Patented July 21, 1914.

Application filed March 12, 1913. Serial No. 753,753.

To all whom it may concern:

Be it known that I, ASHLEY C. BENNETT, a citizen of the United States, residing at Minneapolis, in the county of Hennepin and State of Minnesota, have invented certain new and useful Improvements in Intake-Manifolds, of which the following is a specification.

My invention relates to gas engines and particularly to an intake manifold to be applied to a delivery pipe from a carbureter and conduct explosive mixture to a plurality of engine units.

It is the primary object of my invention to provide a manifold delivery pipe in which are formed a series of preferably flat-bottomed ducts. When burning heavy oils where a manifold intake is used there may be, especially at slow speeds, a considerable amount of condensation. If the manifold pipe is formed in the usual way, as a single enlarged passage-way, the condensed liquid will accumulate upon the walls and run to the bottom, where it may gather to such an extent as finally to cause flooding and snuffing of the engine or cause misfiring, especially when the speed of the engine is increased. By my invention of dividing the carbureter passage-ways into a series of small channels each preferably provided with a flat bottom, I enormously increase the surface upon which the products of condensation would collect, and correspondingly increase the area from which evaporation may take place. The result of this is that where condensation occurs the condensed liquid will be spread in extremely thin films over a large extent of surface and will have no opportunity to collect in any considerable body, so that when the engine speed is increased the resulting increase in the velocity of the air passing through the passages will break up and evaporate these thin films of condensation and carry the same to the explosion chambers in a properly vaporized condition for complete combustion.

It is also an object of my invention to provide a manifold in which a throttling action may take place for varying the extent of opening to the several intake ports, and yet such that the area of passage-way through which the gas flows will be constant throughout the extent of such passage-ways however much the manifold may be throttled or diminished in extent.

The full objects and advantages of my invention will appear in connection with the detailed description thereof and are particularly pointed out in the claims.

In the drawings, illustrating the application of my invention in one form, Figure 1 is a section through a manifold employing the principles of my invention. Fig. 2 is a section on line 2—2 of Fig. 1. Fig. 3 is a section on line 3—3 of Fig. 1. Figs. 4 and 5 are sectional views showing variations in the arrangement of the passage-ways.

A pipe 10 leading from a carbureter, not shown, of any desired construction communicates through a port 11 with a chamber 12 centrally positioned in respect to manifold pipes 13 and 14, it being understood that any desired number of such manifold pipes may communicate with the central chamber 12. The manifold pipes 13 and 14 may connect by means of extensions 15 with admission pipes 16 for the various engine units; explosive mixture which enters the chamber 12 from the carbureter pipe 10 may, therefore, flow through pipes 13 and 14 and extensions 15 to the various admission pipes 16. The pipes 13 and 14 may, as indicated in Figs. 2, 3 and 4, be of rectangular cross section; or, as indicated in Fig. 5, may be cylindrical. In either event a series of horizontal partitions 17 are provided and corresponding vertical or transverse partitions 18 within the pipes 13, 14, etc., dividing said pipes into a multiplicity of elongated flat-bottomed ducts. These partitions may be formed directly by casting or may conveniently be formed as shown in Fig. 4 by bending sheet metal with a series of loops 19 resting upon the bottom 20 of the pipe or horizontal top portions 21 of the plate below. However the partitions are formed, they will provide a series of passage-ways 22 extending through the pipes 13, 14, etc., and of uniform cross sectional area from the chamber 12 to the admission valves 16. These passage-ways will preferably be provided with flat bottoms so that any liquid which condenses will be held in thin, attenuated films upon which the gas flowing through the same may operate to break up and evaporate such films of liquid.

A feature of additional advantage in my structure is comprised in its adaptability for throttling the manifold without reducing the velocity of gas going through the same. As indicated in Figs. 1 and 2 the chamber

12 is extended upwardly into a valve casing 24 in which is positioned a piston valve operated by a rod 26 connected with control mechanism of common construction. When 5 the valve 25 is pushed downwardly within the chamber 12, it will successively cut off passages 22 within pipes 13 and 14. This will, of course, reduce the aggregate area of the manifold pipes through which explosive 10 mixture may flow, but will reduce this area throughout the length of the manifold pipes so that the gas that actually is delivered to the admission pipe 16 will travel at the same velocity whatever the extent of closure effected by valve 25.

The operation of my device will readily be apparent, and its utility where heavy oils such as kerosene are employed in connection with the use of an intake manifold is 20 obvious. The manifold may be constructed with very little additional cost over that entailed in the usual construction of undivided pipes, and will very largely increase the efficiency of such manifold when in use.

25 It is to be noted that the valve 25 may be spring or gravity held, as indicated, so that the same will be lifted by the suction pressure and will of course be lifted to a greater degree in proportion to the force of 30 the suction pressure, only reaching the highest elevation in which all of the mouths of the ducts are exposed when the engine reaches such a high speed as to induce practically the maximum suction pressure. That 35 is, the valve 25 will by its own weight as constructed normally descend into the chamber 12 thereby closing all excepting the bottom tier of the passageways 22. When the engine is operated, the suction blast coming 40 through pipe 11 under valve 25, will lift said valve to a greater or less extent in accordance with the force of this suction pressure proportionately opening a greater or less number of the passages 22.

45 I claim:

1. An intake manifold comprising a casting formed with a central chamber, means for introducing explosive mixture into said chamber, a plurality of manifold pipes leading from said central chamber, and means dividing the space within said pipes throughout their lengths into a multiplicity of ducts or passageways.

55 2. An intake manifold comprising a casting formed with a central chamber, means for introducing explosive mixture into said chamber, a plurality of manifold pipes leading from said central chamber, and means dividing the space within said pipes throughout their lengths into a multiplicity of flat-bottomed ducts or passageways.

60 3. An intake manifold comprising a casting formed with a central chamber, means for introducing explosive mixture into said chamber, a plurality of manifold pipes lead-

ing from said central chamber, and two sets of angularly disposed partitions dividing the space within the said manifold pipes into a multiplicity of flat-bottomed passage-ways.

70 4. An intake manifold comprising a casting formed with a central chamber, means for introducing explosive mixture into said chamber, a plurality of manifold pipes leading from said central chamber, and two sets 75 of partitions disposed at right angles to one another within the manifold pipes dividing the space within said pipes throughout the length of the same into a multiplicity of rectangular ducts or passage-ways.

80 5. An intake manifold comprising a casting formed with a central chamber, means for introducing explosive mixture into said chamber, a plurality of manifold pipes leading from said central chamber, two sets of partitions disposed at right angles to one another within the manifold pipes dividing the space within said pipes throughout the length of the same into a multiplicity of rectangular ducts or passage-ways, said ducts or passage-ways for each manifold pipe having the mouths opening into the central chamber in common planes, and a valve 85 operative in said chamber for closing said mouths as desired.

90 6. An intake manifold comprising a casting formed with a central chamber, means for introducing explosive mixture into said chamber, a plurality of manifold pipes leading from said chamber, sets of partitions in the manifold pipes dividing the space within said pipes throughout the length of the same into a multiplicity of ducts or passageways, said ducts or passageways for each manifold 95 pipe having the mouths opening into the central chamber in common planes, and a valve operative in said chamber and tending to close the mouths of said ducts but operated under suction pressure to open a 100 larger or smaller area of said mouths in proportion to the pressure induced by the operation of the engine.

110 7. An intake manifold comprising a casting formed with a central chamber, a carburetor pipe opening into said chamber, a plurality of manifold pipes leading from said chamber, means dividing each of said manifold pipes into a multiplicity of ducts or passageways, said ducts or passageways for each manifold pipe having mouths thereon opening into the central chamber in common planes across said manifold pipes, and a valve plug slidable in said chamber and having walls operative over said mouths 115 of each manifold pipe and adapted to close and open progressively the ducts of each manifold pipe in the same proportion.

120 8. An intake manifold comprising a pipe having therein an open chamber, a car- 130

bureter delivery pipe opening into said chamber, a series of independent ducts formed within said manifold pipe and having their mouths opening into the said chamber, and a valve operative in said chamber for closing a greater or smaller number of said mouths, as desired.

In testimony whereof I affix my signature in presence of two witnesses.
